UNITED STATES PATENT OFFICE

FRANK M. ROBY, OF CLEVELAND, OHIO

LOW WATER ALARM

Application filed October 21, 1927. Serial No. 227,760.

This invention relates to a low water alarm for steam boilers, but is shown particularly in this application as designed for use with locomotive boilers. A satisfactory low water alarm for locomotive boilers is illustrated in the patent of Herman B. Thurston No. 1,684,897, issued September 18, 1928. Briefly, such alarm embodies a reservoir which is mounted outside the boiler and above the normal water level thereof. A float actuated valve is mounted within the reservoir and is adapted to control the operation of an alarm when the water level in the boiler drops to a pre-determined point. Such reservoir has a fill pipe which communicates with the boiler below the normal water level thereof, and the area of an opening into the fill pipe is so arranged that there is a pre-determined interval of time between the uncovering of the bottom of the fill pipe and the sounding of the alarm. This prevents operation of the alarm when the water surges toward the forward end of the boiler, and thereby reduces the depth over the crown sheet for a short interval of time.

In the operation of such alarm, it has been found that the evaporation of any water passing through the opening of the whistle valve, or any slight leakage of water past the valve seat caused a deposit that in time would prevent the passage of sufficient steam to properly sound the alarm whistle. Moreover, any material which may be in solution, or which may be left as a deposit tended to accumulate upon the valve seat and to hold the alarm valve open.

An object of the present invention is to make certain improvements or refinements of construction in the alarm illustrated in the Thurston application, so as to permit proper operation of the alarm even in the so called bad water districts when treated water is customarily used.

Another object is to make certain improvements in mechanical construction which will protect the operating parts from damage either while the alarm is in operation, or while the operating parts are removed from the reservoir casing.

The preferred construction of alarm em-

bodying my invention is illustrated in the drawings, wherein Fig. 1 is a cross sectional diagram of a locomotive boiler showing the usual position in which this type of alarm is mounted on the boiler; Fig. 2 is a plan view of the alarm apart from the boiler; Fig. 3 is an end view of the alarm on an enlarged scale; Fig. 4 is a vertical transverse section through the alarm; Fig. 5 is a vertical longitudinal section through the alarm and is taken more particularly on a plane indicated by the line 5-5 in Fig. 4; Fig. 6 is a horizontal view taken on a plane indicated by the line 6-6 in Fig. 5; Fig. 7 is an enlarged detailed sectional view of the alarm adjacent the valve chamber; Fig. 8 is a vertical transverse section taken through the alarm on a plane indicated by the line 8-8 in Fig. 7; Fig. 9 is a horizontal section through part of the float rod guide, more particularly is a section taken on a plane indicated in the line 9-9 in Fig. 4; and Fig. 10 is an enlarged detailed vertical section through the device adjacent the valve chamber showing a modified form of connection between the valve head and float; Fig. 11 is a sectional detail on an enlarged scale of a split bushing used in the construction; Fig. 12 is a transverse section, as indicated by the lines 12-12 on Fig. 11.

The boiler illustrated, indicated in general at 10, has a roof sheet 11 and a crown sheet 12. The alarm shown comprises a water reservoir 13 which is mounted outside the boiler and above the normal water level thereof. The interior of the reservoir is arranged to be connected to the interior of the boiler by a fill-pipe 14, the lower end of which terminates below the normal water level of the boiler. The top of the fill-pipe is indicated at 15 as terminating adjacent the top of the reservoir, and more particularly directly beneath and in line with a removable plug 16 in a closure plate 17. The purpose of such plug is to permit the interior of the fill-pipe to be cleaned from a point outside the boiler. In the preferred form, such fill-pipe comprises two sections, the upper of which is indicated at 18 as being connected to the reservoir at 19, and the lower of which, hereto-

fore indicated at 14, is attached to the reservoir at 20. Between the points 19 and 20 there is formed a chamber 21 in the casing, and such chamber is arranged to be in communication with the main reservoir through an opening 22. The area of such opening controls the rate at which water may leave the reservoir and flow back into the boiler.

The rise and fall of water in the reservoir is utilized for controlling the rise and fall of a float 25, which in turn operates the alarm valve. In the present embodiment, such valve is indicated in Fig. 7 as a head member 26 and a seat member 27. The head and seat members are mounted in a valve chamber 28 which is separated from the main reservoir. By maintaining the valve chamber apart from the main reservoir and by providing proper drainage back of the boiler from the valve chamber for the water entering from the main reservoir around the reduced section of the valve stem, there would be no opportunity for water to accumulate in the valve chamber, and thereby to form a deposit on the valve seat, or subsequently in the passage-way to the alarm whistle, which may interfere with the proper operation of the valve or alarm whistle.

The valve head is connected to the float in such manner that vertical movement of the float will effect rectilinear movement of the head. A simple way of making such connection is to so make the float rod 24 that it terminates in a yoke adjacent the valve end thereof. The lower end of the yoke portion is then pivotally mounted, as at 30, to the plate 31 which forms an end closure for the reservoir. The upper end of the yoke is pivotally connected, as at 39, to the valve stem 32. A yoke shaped keeper 33 then extends downwardly along the outer sides of the yoke portions and keeps the pins from falling out of place and at the same time obviates the necessity for cotter pins and the like, which otherwise would be required for holding such pins in place.

As heretofore explained, the valve rod and stem assembly is mounted on the plate 31 which is fastened by suitable securing members 35 to the end of the reservoir. In order therefore to protect the valve stem in the event such plate is removed from the casing, I have shown a projection 36 which extends inwardly from the plate and serves to engage the undersurface of the float rod 24, and prevent excessive outward movement of the valve stem with reference to the plate, so that the stem cannot bind in the split bushing 57 or become bent.

To prevent the sides of the float from engaging the casing while moving therein, I employ a guide member 40 which preferably extends downwardly from the closure plate 17 and terminates above the bottom of the casing. The lower end of such member is

bifurcated, as at 41, and such bifurcated portions function as lateral guides for the float rod 24. To minimize friction such guides are shaped to make a thin edge 42 (Fig. 9) along that portion which may be in contact with the rod.

To prevent the accumulation of sediment at the bottom of the casing from forming a suction which may tend to hold the float in lowered position, I provide an abutment 45 at the bottom of the casing. The top of such abutment is above the bottom of the blowout opening 46. This provides a support for the float and enables it to be operated in a satisfactory manner, notwithstanding the usual accumulation of sediment.

In practice, the valve chamber being subjected to high pressure steam, and the float chamber being subjected to the same pressure, it would appear that the pressure in the valve and float chambers would be equal. However, as a matter of fact, the large float chamber offers more surface for condensation of steam therein, and hence there is a slightly lower pressure in the float chamber than in the valve chamber. As a result, there is a tendency for steam to flow from the valve chamber into the float chamber faster than the float chamber would be able to condense it and thus interfere with the float chamber completely filling with water, at it should do for the normal operation of the alarm.

I have found that if the valve stem is substantially the same diameter as the valve head, and if even only a few thousandths of an inch clearance is permitted between the stem and the bushing, that such clearance area will allow sufficient steam to flow from conduit 51 through the valve chamber and back into the float chamber to prevent the water from rising to the top of the float chamber. I prevent the passage of steam in such quantities by utilizing a shank having a reduced diameter from that of the head, and by utilizing a split bushing 57 which is shown as being threaded into the plate 31 and as having an opening 8, Figs. 7, 11 and 12, which is only large enough to permit the shank to have a tight sliding fit therein. Any irregularities in alignment are compensated for by enlarging the opening in the pivotal end 7 of the shank, such end being held in place by the pivot pin 39. In this way excess steam cannot flow from the valve chamber into the float chamber and interfere with the proper filling of the float chamber with water.

In the normal operation of a device of this character, assuming that the boiler is filled to its normal level with water, as the steam pressure rises the water will be forced upwardly through the fill-pipe and into the reservoir. As the float rises with the water it shuts off the alarm valve and maintains it shut so long as the water remains at a predetermined level in the reservoir. If the water

falls below the lower end of the fill-pipe 14, then the reservoir will drain comparatively slowly through the opening 22. The reservoir will therefore drain in proportion to the size of the opening and the water in the reservoir will gradually fall to the point where the float opens the alarm valve by withdrawing the valve stem 26. As soon as such valve is opened then steam will flow into the alarm conduit 50 and thus sound the alarm whistle 54. Normally, the valve chamber is subjected to steam pressure at all times by reason of the fact that a conduit 51 is directly connected to the steam space in the boiler at connection 52. Such conduit functions in a satisfactory manner to drain the valve chamber.

For purposes of testing the alarm at any time, without having to lower the water in the boiler, steam may be introduced into the upper portion of the reservoir thru the pipe 55 shown particularly in Fig. 5 under the control of a hand valve 56. The pipe 55 communicates with the steam portion of the boiler or with a steam line and the valve 56 is closed except for test purposes. On opening the valve the steam entering the top of the reservoir will release the hydrostatic head and permit the water to flow through the opening 22 until the float actuates the valve stem 26, thus opening the valve and causing the alarm to be sounded. Upon closing the hand valve 56 the reservoir again fills with water as previously described, thus raising the float and closing the alarm valve. The escape of the water from the reservoir and the operation of the alarm is exactly the same, when using the test valve, as when due to a low water condition in the boiler.

In Fig. 10 I have shown a modified construction for connecting the valve stem to the float rod. Such construction, instead of employing an opening in split bushing 57, as shown in Fig. 7, comprises a diaphragm 60 which is attached respectively to the valve stem 26a and to the end plate 31a. This diaphragm then seals off the connection between the float chamber and the valve chamber and prevents passage of any water from the float to the valve chamber. This insures a clean valve seat and steam outlet to whistle at all times, since the valve is subjected only to dry steam.

A low water alarm made in accordance with my invention is advantageous in that it maintains the valve constantly in an atmosphere of dry, live steam and thus prevents any deposit on the valve seat which might interfere with the proper seating of the valve. I accomplish this result without danger of the live steam leaking along the valve stem into the float chamber and interfering with the proper functioning of the latter. Moreover the mechanical improvements set forth herein serve to assure proper operation of the

float and valve as well as to protect the valve when the assembly is removed from the casing.

I claim:

1. A device of the character described, comprising a reservoir, an alarm indicating member, a valve for controlling said member, a stem associated with said valve and a float in the reservoir for operating the valve, a connection between the float and valve comprising a pivoted float lever having an arm portion extending transversely to the valve stem, a removable pin connecting the arm and valve stem and a U-shaped keeper removably mounted on the float lever and overhanging the opposite ends of the pin to retain the same in place. 70

2. In a device of the character described, the combination with a reservoir casing, of a float arranged to be moved vertically therein, a float arm, said arm being forked at the end opposite the float and being pivotally connected to one wall of the casing, a valve stem extending through said wall and between the forked portions of said arm, a pivot pin extending through the forked portions and the valve stem, and a yoke removably connected to the arm and engaging the outer ends of said pivotal connections for holding the same in place. 85

3. In a device of the character described, the combination of a reservoir, a float operable therein, a valve for controlling a conduit to an alarm indicating device, an arm for the float connected with the valve, and stationary means carried by the casing and standing vertically on opposite sides of the float arm and serving to guide it, said stationary means being formed to present substantially line edges on opposite sides of the float arm. 100

4. In a device of the character described, the combination of a reservoir, a valve, a float within the reservoir, a lever pivoted to the stationary part of the reservoir connecting its free end with the float and having an arm connected with the valve and a narrow abutment carried by the bottom wall of the casing projecting upwardly therefrom and adapted to engage the float in its lowermost position and maintain it distant from the bottom of the reservoir for substantially the whole surface of the float. 115

5. In a device of the character described, the combination with a reservoir casing having one end thereof open, a detachable closure plate therefor, said plate having a valve chamber leading outwardly therefrom, a valve in said chamber, a float pivotally mounted on the reservoir side of the plate, a valve stem extending through the plate and being operatively connected to the float, and means carried by said plate on the reservoir side thereof for limiting movement of 120

the float in a downward direction when the plate is detached from the casing.

6. In a device of the character described, the combination with a boiler, of a reservoir mounted thereon and at a higher level than the normal low water level of the boiler, a hollow sealed float within said reservoir but having no portion of the same at a higher level than the top of said reservoir, a valve chamber separate from the reservoir and having a valve seat therein, and spaced from the wall of the chamber, whereby the seat is surrounded by the chamber, there being a split bushing which is provided with a narrow passageway therethrough extending between the reservoir and the valve chamber, a valve stem having enlargements on its opposite ends and a reduced integral intermediate portion arranged to extend through the passageway and having a valve member on one end thereof and within the valve chamber, and having the other end thereof within the reservoir, an arm rigidly connected at one end thereof to the float and pivotally connected at the other end thereof to the wall of the reservoir, said arm being also pivotally connected to the valve stem, whereby the movement of arm in a vertical plane and in a plane of the valve stem transmits a substantially horizontal movement to the valve stem, a conduit leading from the reservoir into the boiler and terminating below the normal low water level of the boiler, and another conduit leading from the valve chamber and terminating within the boiler above the normal water level thereof, said last named conduit functioning to drain the valve chamber and to supply steam thereto, an alarm indicating member connected to the valve chamber, said member being adapted to be actuated by steam from said chamber when the valve is opened, and said valve being adapted to be controlled by the rise and fall of water within the reservoir and independently of the pressure within the reservoir.

7. The combination with a boiler, of a reservoir disposed above the normal water level of the boiler, a hollow sealed float within said reservoir, a conduit leading from the reservoir to the interior of the boiler and terminating below the normal water level thereof, an alarm indicating member, a valve chamber associated with said alarm indicating member and located adjacent to but separate from the reservoir, said chamber being arranged to communicate with said member, a wall separating the reservoir from the valve chamber, a split member in said wall and provided with an aperture therethrough, a valve stem provided with a reduced intermediate portion arranged to pass through the aperture in said split member whereby a tight sliding fit between the stem and said split member is provided, a valve mounted

within the valve chamber and arranged to be actuated by said stem, said stem being arranged to be actuated by the float consequent upon the rise and fall of water in the reservoir for controlling the operation of the indicating member, and independent means connecting the valve chamber to a source of steam supply.

In testimony whereof, I hereunto affix my signature:

FRANK M. ROBY.
